UNITED STATES PATENT OFFICE.

JOHN J. CONWAY, OF BRIDGEPORT, CONNECTICUT, ASSIGNOR TO THE ACME SHEAR COMPANY, OF BRIDGEPORT, CONNECTICUT, A CORPORATION OF CONNECTICUT.

PIVOT FOR SCISSORS AND SHEARS.

1,272,385.

Specification of Letters Patent. Patented July 16, 1918.

Application filed December 5, 1917. Serial No. 205,660.

To all whom it may concern:

Be it known that I, JOHN J. CONWAY, a citizen of the United States, residing at Bridgeport, county of Fairfield, State of Connecticut, have invented an Improvement 5 in Pivots for Scissors and Shears, of which the following is a specification.

This invention relates to scissors and shears and has for its object to render them 10 more attractive and desirable by providing the pivots with inset jewels.

With these and other objects in view, I have devised the novel jeweled pivot for 15 scissors and shears which I will now describe referring to the accompanying drawing forming a part of this specification and using reference characters to indicate the several parts.

Figure 1 is an elevation, showing the application 20 of my invention to a pair of shears,

Fig. 2 a section on an enlarged scale, on the line 2—2 in Fig. 1, looking in the direction of the arrows,

Fig. 3 a perspective view of the pivot and 25 jewel before assembling, and

Fig. 4 is a view showing the application of the invention to a pair of scissors.

10 denotes the blades of a pair of scissors or shears and 11 the pivot. The pivot is 30 threaded at one end and is engaged by a nut 12, which is usually locked in place by upsetting the end of the pivot. The head of the pivot is preferably, although not necessarily, beveled on its edge. The essential

feature of the invention is that I provide 35 the head of the pivot with a socket 13 to receive a jewel 14. The jewels are shaped to imitate a gem and are colored in imitation of rubies, emeralds, sapphires, etc., or are uncolored in imitation of diamonds. The 40 jewel of each pivot is secured in place by cement indicated by 15, the rim of the socket retaining the jewel securely in place and preventing its dislodgment. The base of the socket is preferably provided with 45 a recess 16 which is filled with cement and adds to the security of the jewel in its setting.

Having thus described my invention, I claim:—

1. A device of the character described comprising a body provided with a head at one end and threaded at the other end, said head having a socket therein, a jewel within said socket, and means for maintaining a body of cementing material within 50 said socket and in contact with the base of the jewel.

2. A device of the character described comprising a body provided with a head at 60 one end and threaded at the other end, said head having a socket therein provided with a recess in its bottom, a jewel within said socket, and a cementing material within 65 said recess and attached to the base of the jewel.

In testimony whereof I affix my signature.
JOHN J. CONWAY.
